(57) **CLAIM**

The ornamental design for a human-machine interface for electrical protection devices, as shown and described.

DESCRIPTION

FIG. 1 is a perspective view of a first embodiment of a human-machine interface for electrical protection devices;

FIG. 2 is a front view of said first embodiment of a human-machine interface for electrical protection devices;

FIG. 3 is a rear view of said first embodiment of a human-machine interface for electrical protection devices;

FIG. 4 is a bottom view of said first embodiment of a human-machine interface for electrical protection devices;

FIG. 5 is a top view of said first embodiment of a human-machine interface for electrical protection devices;

FIG. 6 is a right view of said first embodiment of a human-machine interface for electrical protection devices;

FIG. 7 is a left view of said first embodiment of a human-machine interface for electrical protection devices;

FIG. 8 is a perspective view of a second embodiment of a human-machine interface for electrical protection devices;

FIG. 9 is a front view of said second embodiment of a human-machine interface for electrical protection devices;

FIG. 10 is a rear view of said second embodiment of a human-machine interface for electrical protection devices;

FIG. 11 is a bottom view of said second embodiment of a human-machine interface for electrical protection devices;

FIG. 12 is a top view of said second embodiment of a human-machine interface for electrical protection devices;

FIG. 13 is a right view of said second embodiment of a human-machine interface for electrical protection devices;

FIG. 14 is a left view of said second embodiment of a human-machine interface for electrical protection devices;

FIG. 15 is a perspective view of a third embodiment of a human-machine interface for electrical protection devices;

FIG. 16 is a front view of said third embodiment of a human-machine interface for electrical protection devices;

FIG. 17 is a rear view of said third embodiment of a human-machine interface for electrical protection devices;

FIG. 18 is a bottom view of said third embodiment of a human-machine interface for electrical protection devices;

FIG. 19 is a top view of said third embodiment of a human-machine interface for electrical protection devices;

FIG. 20 is a right view of said third embodiment of a human-machine interface for electrical protection devices;

FIG. 21 is a left view of said third embodiment of a human-machine interface for electrical protection devices;

FIG. 22 is a perspective view of a fourth embodiment of a human-machine interface for electrical protection devices;

FIG. 23 is a front view of a fourth embodiment of a human-machine interface for electrical protection devices;

FIG. 24 is a rear view of said fourth embodiment of a human-machine interface for electrical protection devices;

FIG. 25 is a bottom view of said fourth embodiment of a human-machine interface for electrical protection devices;

FIG. 26 is a top view of said fourth embodiment of a human-machine interface for electrical protection devices;

FIG. 27 is a right view of said fourth embodiment of a human-machine interface for electrical protection devices; and,

FIG. 28 is a left view of said fourth embodiment of a human-machine interface for electrical protection devices;
